UNITED STATES PATENT OFFICE.

PHILIP G. GRAF, OF NORTH CANTON, OHIO, ASSIGNOR TO THE HOOVER COMPANY, OF NORTH CANTON, OHIO, A CORPORATION OF OHIO.

MECHANICAL DEMONSTRATING MACHINE.

Application filed October 15, 1923. Serial No. 668,468.

To all whom it may concern:

Be it known that I, PHILIP G. GRAF, a citizen of the United States, and a resident of North Canton, in the county of Stark and State of Ohio, have invented a new and useful Improvement in Mechanical Demonstrating Machines, of which the following is a full, clear, and exact description.

The object of this invention is to provide a machine for mechanical demonstration of suction sweepers or other machines which are reciprocated back and forth in their operation.

It is the desideratum in the operation of such a machine to approximate as nearly as possible actual operating conditions as usually encountered therefor.

A further object of my invention is to as closely as possible approximate actual operating conditions of the machine being demonstrated.

For a complete description of my machine reference is had to the accompanying drawings, in which like numerals indicate like parts throughout and wherein—

Fig. 1 is a complete demonstrating unit in side elevation,

Fig. 2 is an end elevation of the structure shown in Fig. 1,

Fig. 3 is a detail partly in section showing the gear reduction,

Figs. 4 and 5 are elevation and plan views, respectively, of details of the ratchet operating mechanism, and

Fig. 6 is an elevation of the cam for operating the ratchet mechanism.

In the drawings there is shown a table-like structure indicated generally as 10 having top 11 and legs 12.

Under the table top and longitudinally thereof there is mounted a relatively large roller. Near each side edge of the table is mounted a smaller roller 14 and parallel to but slightly separate from large roll 13 is adjustably mounted a third small roller 15 which by means indicated generally at 16 may be moved toward or away from large roll 13.

On one end of large roll 13, there is provided a ratchet wheel 17, the teeth of which are not shown because of the small scale of the drawings, which ratchet wheel is operated by pawl 18 mounted on the upper end of push rod 19 supported in guide 20. The lower end of this push rod is provided with

a transverse slot at 21. This slot receives a pin 22 by means of which reciprocating movement is imparted to rod 19. Reciprocating motion is imparted to the pin 22 by means of cam 23.

Pin 22 is mounted in the outer end of pivoted arm 24 pivoted at 25. The outer end of arm 24 is bifurcated at 26 and provided with depending portions 27 which straddle cam 23 and act to guide roller 28 on the periphery of cam 23. Roller 28 is mounted on pin 22 which passes through the bifurcated ends 26 of arm 24 and the inner end of this pin cooperates with slot 22 of push rod 19. Between the lever 24 and a stationary portion of the structure, there is interposed spring 50 whose function is to maintain contact between roller 28 and the race of cam 23. For revolving cam 23 there is provided a motor 30 mounted on main table frame 10 which through a worm and worm wheel reduction 31 rotates shaft 32 on which the cam 23 is mounted.

When an endless carpet 29 is placed on rolls 13, 14, 14 and made taut by proper adjustment of adjustable roll 15 by adjusting means 16, starting of the motor will cause a step by step movement of carpet 29. Rotation of cam 23 causes through roller 28 and pin 22 a reciprocation of push rod 19 which through pawl 18 and ratchet wheel 17 imparts step by step movement to large roll 13 thereby moving the carpet correspondingly.

The structure for imparting a forward and backward motion to the machine being demonstrated such as a suction cleaner 33 will now be described.

On shaft 32 of the worm reduction there is secured crank 34, to which is pivotally connected one end of link 35 the other end pivotally connecting as at 36 to lever 37 pivotally mounted at 38 on main frame 10. The handle of the machine to be demonstrated is pivotally connected at 39 to the upper end of lever 37 and there is provided at this point a counting mechanism generally indicated at 40.

The operation of the entire structure described when the motor is started is to cause arm 37 to oscillate, which moves the machine, being demonstrated, backward and forward over the carpet which is given a step by step motion as previously explained. Cam 23 is so designed that the step by step

movement is imparted to the carpet when the wheels of the machine being demonstrated are off the carpet at each the front and rear end of its traverse. If the cam is not 5 designed this way there is a very undesirable side twist transmitted to lever 37.

At its forward end table 10 is provided with a mirror 41 pivotally mounted at 42 and lights 43 are provided, the whole 10 mounted in housing 44. The purpose of this last structure is to show operating parts of the bottom of the machine when the same are visible from the bottom, the stroke of the demonstrating machine being such that 15 the front part of the machine demonstrated projects over the edge of the table at the forward end of the stroke.

If desired, the top 11 of the table may be 20 covered beyond the edges of the carpet with a sound deadening material such as rubber.

Having fully described the construction and operation of my invention—

I claim:—

1. The combination of an article to be 25 used on carpets and mechanism for demonstration thereof, means for causing reciprocation of the article, a portion of the mechanism for demonstrating comprising a carpet over which the demonstrated article is reciprocated, the mechanism for demonstrating having means causing progressive step-by-step movement of the carpet in timed relation to reciprocations of the article there-over.

2. Structure as claimed in claim 1 wherein 30 the means for causing step by step movement of the carpet comprises cam, pawl and ratchet wheel mechanism.

3. Structure as claimed in claim 1 where- 40 in the means for reciprocating the article comprises an oscillating lever.

4. Structure as claimed in claim 1 where- 45 in the means for causing step by step movement of the carpet comprises cam, pawl

and ratchet mechanism and wherein the 45 means for reciprocating the article comprises an oscillating lever.

5. The combination of a device for the display of a structure and a structure to be displayed, the device comprising a sta- 50 tionary platform and a movable platform on which the structure is displayed, the movable platform covering a portion of the stationary platform, means to cause recipro- 55 cation of the structure displayed and means for causing lateral movement of the movable platform over the stationary platform.

6. The combination of a device for the display of a structure and a structure to be displayed, the device comprising a station- 60 ary platform and a movable platform on which the structure is displayed, the movable platform covering a portion of the stationary platform, means to cause recipro- 65 cation of the structure displayed and means for causing lateral movement of the movable platform over the stationary platform in timed relation to the reciprocation of the structure displayed.

7. A display device for suction cleaners 70 comprising a mechanism adapted to recipro- cate the cleaner along a fixed path, a laterally movable carpet positioned to form a part of said path, and means to shift said carpet laterally when the cleaner is at the 75 end of the stroke of the cleaner.

8. A mechanical device for operating suc- 80 tion cleaners comprising a support for floor coverings, means to impart a to and fro movement of the suction cleaner over the floor covering, and means for laterally shifting the floor covering at the end of each to and fro movement of the cleaner.

Signed at Chicago, in the county of Cook and State of Illinois, this 11th day of Octo- 85 ber A. D. 1923.

PHILIP G. GRAF.
